UNITED STATES PATENT OFFICE.

JNO. DEMAREST, OF MOTT HAVEN, NEW YORK, ASSIGNOR TO THE J. L.
MOTT IRON WORKS.

IMPROVED FLASK FOR MOLDING BATH-TUBS.

Specification forming part of Letters Patent No. 13,514, dated August 28, 1855.

To all whom it may concern:

Be it known that I, JOHN DEMAREST, of Mott Haven, Westchester county, and State of New York, have invented certain new and useful improvements in three part flasks for molding and casting bath-tubs and other thin and deep hollow castings presenting a great extent of surface and requiring three-part flasks, of which the following is a full, clear, and exact description, reference being had to the accompanying drawings, making a part of this specification, in which—

Figure 1 is a top view of a three-part flask for casting bath-tubs; Fig. 2, a like view with the cope or third section removed; Fig. 3, a like view with the cheek or second section removed; and Figs. 4 and 5 vertical sections taken at the lines A a and B b of Fig. 1.

The same letters indicate like parts in all the figures.

The molding of bath-tubs and other large and thin hollow articles requiring three-part flasks has heretofore been attended with serious difficulties. The three parts or sections of the flask are rectangular wooden frames, the sides of which readily yield to pressure, and the whole mold when complete is very heavy, so that in the process of molding and in moving the flask the sides yield, so that the accuracy of the mold is destroyed, and the article when cast is too thin and weak in some parts and too thick and heavy in others, and such inaccuracies in the mold, if not discovered before casting, cannot be remedied without remolding. Again, the sand forming the sides of the mold, particularly where it overhangs by reason of the inclination or curvature of the sides, is liable to "cave in," as it is termed, thus destroying the mold in whole or in part.

The object of my invention is to avoid these inconveniences; and it consists in connecting the sides of the drag or first section of the flask and the cope or third section of the flask, or either, with a cross brace, bar, or bars, to prevent them from yielding to any pressure or strain to which they may be subjected, in combination with clamps and clamp-screws attached to the sides of the drag and cope, or either, and embracing the cheek or second section of the flask, which is not braced, so that the sides of this second section can be thus held and adjusted at pleasure by the

clamp-screws or their equivalents, and thus effectually prevent the flask from being strained to change the form of the mold after it has been completed, while at the same time the sides can be adjusted to equalize the sides of the mold, if from any cause it should be found that one side of the mold is of greater thickness than the other; and my said invention consists in preventing the sides of the sand mold inside of the flask from "caving in," as it is termed, by recessing or cutting out the upper edge of the vertical wings which project inside of the cheek or second section of the flask, leaving the upper edge near the inner edge the highest, so that the union of the sand over these recessed edges of the wings will effectually sustain the sides of the molds and prevent them from caving in.

In the accompanying drawings, *a* represents the drag or lower section of the flask, which is to be filled and rammed down to receive the pattern of the bath-tub *b* or other article with the upper edge downward. Across the middle of the length there is an iron brace-bar, *c*, firmly secured to the sides to keep them from being strained apart by any force applied inside or outside. This brace may be of any desired breadth; or several of them may be inserted at different portions of the length; and to the outside are secured iron clamps *d*, that extend above the upper edge, and there provided with clamp-screws *e e*. The cheek or middle section, *f*, of the mold is formed, as usual, of two side boards, *g g*, and two end boards, *h h*, and fits onto the upper edge of the drag *a* and within the clamps *d d*, so that the ends of the clamp-screws *e e* shall bear against and hold the sides *g g* to prevent them from yielding to the pressure within. The cope *i* or third section is also a rectangular frame, as usual, fitted to rest on the upper edge of the second section, and connected therewith by hooks *j*, as the second section is connected with the first. The sides of the cope, like the sides of the drag, are firmly connected together by a cross brace-bar, *k*, placed across the middle of the length, and, if desired, others may be placed at different parts of the length. The sides are provided outside with clamps *l l*, lapping over the sides of the second section, and provided with clamp-screws *m m*. The opposite sides of the first and of the third sec-

tions being thus bound together by the cross-braces, and provided with clamps and clamp-screws, which embrace and bear against the sides of the second section, which cannot be braced inside on account of the mold which is to be formed therein, and which occupies the whole or nearly the whole depth, keeps them in place and prevents all yielding to internal pressure, whether produced by ramming down the sand in molding the pattern, or in moving the flask during the process of molding, or to the pressure of the molten metal in casting. And, again, what is of great importance, if by any reason it should be found that the mold is of unequal thickness on the two sides, by means of the clamp-screws either of the drag or the cope, or both, the cheek or second section of the flask can be moved laterally to make the two sides of equal thickness, because that part of the mold which determines the form of the inside of the vessel is wholly constructed with the drag or first section, and the part which determines the form of the outside of the vessel is connected with the cheek or second section, the sides of which can yield to the pressure of the clamp-screws. Along the sides of the second section are secured vertical wings *n*, at given distances apart, which project inward to a sufficient distance to sustain the sand which is rammed in to form the sides of the mold, and when required similar wings are also attached to the inner surface of the ends; but for casting bath-tubs, as in the present example, to sustain that part of the end of the mold which determines the form of the head end of the tub, which is a long and gradual curve, the wings *n* project inward from a plate, *p*, attached to the sides near the end. These wings have been heretofore well known and employed for this purpose; but their upper edges have heretofore been made

horizontal, and it frequently happens that the mold is destroyed by the caving in of the sides and ends. To remedy this evil the upper edges of these wings are cut down from the inner edge, as at *q*, so that the sand between the several wings shall be united over these curved edges and bind the whole to prevent the caving in.

I do not wish to be understood as limiting myself to the number and the manner of making and connecting the braces which connect the sides of the drag and cope or first and third sections of the flask, nor to the number and form of the clamps, nor to the use of clamp-screws; nor to the curvature of the upper edge of the wings on the second section of the flask, as it will be obvious that these may be variously changed in form and equivalent means substituted having the same mode of operation and producing like results.

What I claim as my invention, and desire to secure by Letters Patent, is—

1. Connecting by means of a brace or braces the sides of the drag or first section and of the cope or third section of flasks for casting bath-tubs or other large and thin hollow vessels, substantially as described, in combination with the clamps and adjusting-screws or their equivalents which embrace and act upon the sides of the cheek or second section of the flask, substantially as and for the purpose specified.

2. Recessing the upper edge of the wings on the inside of the cheek or second section of the flask back of the inner edge, substantially as and for the purpose specified.

JOHN DEMAREST.
